UNITED STATES PATENT OFFICE.

BENJAMIN SPECTOR AND LOUIS E. ROSENBERG, OF BROOKLYN, NEW YORK.

KNITTED CAP.

1,421,602.

Specification of Letters Patent.

Patented July 4, 1922.

Application filed December 23, 1920. Serial No. 432,668.

To all whom it may concern:

Be it known that we, BENJAMIN SPECTOR, a citizen of Russia, and LOUIS E. ROSENBERG, a citizen of the United States, residing at Brooklyn, in the county of Kings and State of New York, have invented certain new and useful Improvements in Knitted Caps, of which the following is a full, clear, and exact specification.

10 This invention relates to knitted caps, and has for its object to provide a cap of this character which will fit the head of the wearer snugly without undue pressure, and which will cover and protect the ears and 15 back of the neck, being especially suitable for aviators and outdoor workmen and sportsmen.

The cap is made from a strip of knit fabric of zig-zag form consisting of alternating 20 oblique or herringbone transverse areas, the zig-zag parallel edges of the strip being selvages and each having a series of projecting points. In order to make the cap conform to the shape of the human head 25 and cover the ears and back of the neck, some of the projecting points along the selvage edges of the strip are made longer than others by knitting some of the oblique areas of greater extent than others. The 30 margins of the points of one selvage edge are sewed together to form the top of the cap, while the ends of the strip of fabric are also sewed together at the back of the cap.

We have discovered that by having two 35 oppositely inclined or oblique narrow areas of herring-bone weave between successive single wider oblique areas which are in turn woven on opposite inclines, the top of the cap, formed by sewing one selvage of the 40 strip together, will conform more perfectly to the top of the wearer's head without undue stretching of the fabric, than is possible in prior constructions. We have also found that by increasing the number of 45 zig-zag or herring-bone areas in the strip from which the cap is formed, greater elasticity is given to the cap so that it will fit closely to the head of the wearer without producing uncomfortable pressure. Furthermore, we have found that by interposing a pair of oppositely inclined areas of less 50 longitudinal extent between successive oblique areas of greater extent the margin of the cap, constituted by one of the zig-zag selvages of the strip, will fit more closely to the head of the wearer and will

not have the same tendency to curl up that is present where two oppositely inclined areas of greater longitudinal extent come together forming longer points or angular 60 projections at the edge or margin of the cap.

The invention will be first hereinafter described in connection with the accompanying drawings, which constitute part of this 65 specification, and then more specifically defined in the claims at the end of the description.

In the accompanying drawings, wherein similar reference characters are used to 70 designate corresponding parts throughout the several views:—

Figure 1 is a perspective view of the cap as it appears on the head of the wearer.

Figure 2 is a plan view of the strip of 75 fabric from which the cap is formed.

Figure 3 is a front elevation of the cap.

Figure 4 is a side elevation thereof.

Figure 5 is a rear elevation of the cap, and 80

Figure 6 is a top plan view of the same.

The cap 1 is formed from the strip of 85 knitted fabric shown in Figure 2 and which has selvages of zig-zag contour at its upper and lower margins. The central portion of the strip consists of oppositely inclined areas of comparatively little longitudinal extent forming an indentation or re-entrant angle comprising the marginal portions 15 and 16 at the upper edge of the strip, and 90 a projecting point 24 on the lower edge of the strip. At opposite sides of said middle areas of little longitudinal extent there are single oppositely inclined transverse areas of greater extent longitudinally, the upper 95 margins of which are designated 10 and 18 in Figure 2. Next to said areas of greater longitudinal extent come pairs of oppositely inclined transverse areas of less longitudinal extent similar to the middle areas, 100 the said pairs of areas of less extent forming points indicated by the marginal portions 12 and 13, and 21 and 22 on the upper edge of the strip, and notches 25, 25 on the lower edge thereof. Next to these pairs of 105 areas of less longitudinal extent, working from the center towards the ends of the strip, come single oppositely inclined areas of greater longitudinal extent the upper edges of which are indicated at 9 and 19, 110 respectively, in Figure 2, and the extreme end portions of the strip consist of single

transverse oblique areas of less longitudinal extent similar to those already described and which, when the ends 3 and 4 are sewed together in making the cap, constitute a 5 pair of oppositely inclined areas corresponding to the middle pair of the strip, as best shown in Figure 5. The upper edges of said end transverse areas are designated 6 and 7 in Figure 2, while their lower edge portions, when secured together, form a projecting point 26, Figures 4 and 5.

In making up the cap from the strip of herring-bone knitted fabric illustrated in Figure 2, the edges 15 and 16 of the middle 15 transverse areas at the top margin of the strip are sewed together forming the seam 17, Figures 3 and 6, and the edges 6 and 7 are sewed together forming the seam 8 illustrated in Figures 5 and 6 and constituting 20 a continuation of the seam 5 formed by sewing the ends 3 and 4 of the strip to each other. The edges 12 and 13 are sewed to the corresponding length of the edges 9 and 10 forming seams 14 shown in Figures 4 and 25 6, and the remaining portions of said edges 9 and 10 are sewed together forming the seam 11 illustrated in the same figures. In the same manner, edges 21 and 22 are sewed to the corresponding length of the edges 18 30 and 19 forming seams 23 best shown in Figure 6, while the remaining portions of said edges 18 and 19 are sewed to each other to form the seam 20.

The formation of the top of the cap in 35 this way produces a broader and flatter top than in prior constructions, this broader formation of the top making it fit more perfectly to the top of the head of the wearer without undue stretching and without pressing 40 upon the head to a degree apt to cause discomfort. The notches 25 in the margin of the cap make the side portions of said margin cling closely to the sides of the wearer's head below the ears, as shown in 45 Figure 1, so that there is not the tendency for the small points at opposite sides of said notches 25 to curl up after continued wear that there would be if single longer points 50 were present at these points on the margin of the cap.

What we claim is:—

1. A knitted cap comprising a flat strip of fabric of herring-bone weave having pairs of oppositely inclined transverse areas interposed between single oppositely inclined 55 transverse areas of greater longitudinal extent throughout the length of the strip, the ends of said strip and the irregular upper margin thereof being secured together to form the back and top of the cap.

2. A knitted cap comprising a flat strip of fabric of herring-bone weave having parallel zig-zag selvages, said strip being formed with pairs of oppositely inclined 65 transverse areas of small longitudinal extent between successive single transverse areas of greater longitudinal extent which are also oppositely inclined to each other and to adjacent areas of less extent, the ends of the strip being secured together to form 70 the back of the cap, and the adjacent edges of the irregular zig-zag selvage at one edge of the strip being also secured to one another to form the top of the cap, the adjacent zig-zag marginal portions of equal extent being 75 secured to each other and the adjacent marginal portions of unequal extent being secured to each other and the excess of the longer marginal portions which extend beyond said adjacent shorter portions being 80 also secured together for the purpose specified.

3. A knitted cap comprising a flat strip of fabric having successive transverse areas of herring-bone weave of unequal longitudinal 85 extent forming zig-zag parallel selvages, one of said selvages being secured together to form the top of the cap and the ends of said strip being secured together to form the back of the cap, while the other selvage 90 constitutes the edge of the cap, there being single projecting points on said edge of the cap, to cover the forehead and back of the neck of the wearer, alternating with pairs of projecting points of the same size for 95 covering the ears of the wearer.

In testimony whereof we have signed our names to this specification.

BENJ. SPECTOR.
LOUIS E. ROSENBERG.
